[57] **CLAIM**

The ornamental design for a snap top hat, as shown and described.

DESCRIPTION

FIG. 1 is a perspective view of a first embodiment of a snap top hat of this invention, shown on a person's head;

FIG. 2 is a top plan view thereof;

FIG. 3 is a side elevational view thereof;

FIG. 4 is a front elevational view thereof;

FIG. 5 is a rear elevational view thereof;

FIG. 6 is a bottom plan view thereof;

FIG. 7 is a perspective view of a second embodiment of a snap top hat of this invention, shown on a person's head;

FIG. 8 is a top plan view thereof;

FIG. 9 is a side elevational view thereof;

FIG. 10 is a front elevational view thereof;

FIG. 11 is a rear elevational view thereof; and,

FIG. 12 is a bottom plan view thereof.

The broken line showing of the human form is for illustrative purposes only and forms no part of the claimed design.
